CHARLES F. VOLLMER, OF HARRISBURG, PENNSYLVANIA.

Letters Patent No. 72,704, dated December 24, 1867.

IMPROVED EXTENSION BED-LOUNGE.

The Schedule referred to in these Letters Patent and making part of the same.

TO ALL WHOM IT MAY CONCERN:

Be it known that I, CHARLES F. VOLLMER, of Harrisburg, in the county of Dauphin, and State of Pennsylvania, have invented a new and useful Extension Bed-Lounge; and I do hereby declare the following to be a clear and exact description of the nature thereof, sufficient to enable others skilled in the art to which my invention appertains to fully understand and use the same, reference being had to the accompanying drawings, making part of this specification, in which—

Figure 1 is a front elevation of the device illustrating my invention.

Figure 2 is a plan or top view thereof, with the parts laid open.

Figure 3 is a perspective view thereof.

Similar letters of reference indicate corresponding parts in the several figures.

My invention has for its object a lounge, which can be readily extended and formed into a bed. It consists of several new and useful devices, all of which will be hereinafter more fully described.

In the drawings, A represents a lounge, consisting of the seat *a*, back *b*, and head or arm-rest *c*. These parts rest on a base, B, having feet or legs, *d*. The seat, back, and rest are constructed, as ordinarily, of suitable framework, and may be upholstered plain, tufted, or quilted, and with or without springs, as desired. The framework of the seat *a* is hinged to the base B by suitable hinges, *e*, so that the lounge can be readily swung off from the base. The base, B, consists of an open frame, of quadrilateral form, or of form to correspond to that of the lounge. The bottom has secured to it a series of webbing, tapes, or strips, of suitable material, which cross each other and form a sort of net-work, *a'*. The base forms a chamber or open space, C, which receives an extension-mattress, bed, or seat, D. This extension-part D consists of a framework, D', to correspond in shape or form with the base, B, and may be upholstered similarly to the parts *a b c*. Suitable hinges, E, connect the extension-part D and the base B, the butts of which being secured to the under side of the extension-part and the upper side of the base, B, opposite to the hinges *e*, between the base and seat *a*. The extension-part should fit nicely in the base, and be flush with the top thereof. It will readily swing out of the base-chamber, and in a direction opposite to that of the parts *a b c*. F are legs pivoted to one side of the bottom of the frame D' of the extension-part D, and drop into recesses *f* in the said bottom. When the extension D is swung out of its chamber C, the legs F swing from the recesses *f*, and support said part D, but when returned to the chamber, then the legs drop into the recesses and are out of the way. G represents a separate pillow, head, or arm-rest, corresponding in shape with the part *c* of the lounge A. It has toes, *h*, which enter openings or sockets in the head-end of the extension-part D, and thus form a continuation of the head or arm-rest *c*. These toes support the pillow in place, which may be assisted by latches, hooks, eyes, bolts, or any other suitable fastenings, placed on the lower side of the framework of the pillow and the head of the extension D. When the part G is not wanted on the extension, it lies on the head or arm-rest *c*, and acts as an auxiliary or separate pillow.

The operation is as follows: The parts being in position shown in fig. 1, the pillow G is removed and the top, *a b c*, of the lounge A swung back from off the base B, so as to expose the extension-mattress or bed, D, which is then to be drawn out of its chamber C to the full extent. The legs, meanwhile, swing out of the recesses *f*, and, with the hinge E, support the extension D. The top, *a b c*, is then returned on the base, B, and the separate pillow or rest, G, applied to the head of the part D, when my device will assume the form as shown in fig. 3.

The lounge-bedstead, as now arranged, can be readily made to assume its first form by the above operations in reverse order. Remove rest G, swing back the part *a b c*, turn the mattress or bed D into chamber C, and return the part *a b c* on the base B. The rest G can then be placed on the rest *c*, or elsewhere, as may be desired. The extension-part D, when entirely swung out of its chamber, will have its top of the same level as the seat *a*, and thus form a continuation thereof. The back, *b*, may also be hinged, so as to be let down in line with the seat *a*. This will further increase the size of the bed. The hollow base, B, or chamber C, will be made large enough to receive all spreads, quilts, blankets, &c., necessary for the bed. They will lie on the webbing or net-work, or some of them may be placed between the top part, *a b c*, and the extension B, when the latter is in the chamber C.

It will be noticed that when the lounge is in position, as shown in fig. 1, it has the appearance of an ordinary lounge. The extension-part D is entirely concealed, yet is readily accessible.

The simplicity and utility of my invention are apparent. The device can be quickly and cheaply constructed. An ordinary lounge or sofa, of the form now in use, can readily be converted into a bedstead, constructed according to my invention, by merely sawing off the legs or feet and then hinging the frame of the remaining part to the hollow base having the extension-part hinged thereto. The head or arm-rest will act as a pillow, and the back will be serviceable in preventing the person from rolling off of the seat, inasmuch as the upholstering thereof is generally elliptical or semicircular on its upper surface. The pillow G and arm-rest form a head-board, either as a pillow itself, or for preventing an ordinary feather or other pillow, if used, from being slipped off from the bed.

Having thus described my invention, what I claim as new, and desire to secure by Letters Patent, is—

1. An improved extension-lounge, formed by the combination of the following parts: An ordinary top, consisting of a seat, a, arm-rest c, and back b, firmly secured to each other; the extension D, the extension arm-rest or pillow G, the base, B, having bottom a' and the automatic closing and opening legs F, all as herein described.

2. The combination of top, a b c, base, B, extension D, legs f, and pillow G, substantially as and for the purpose described.

To the above I have signed my name, this 21st day of October, 1867.

CHARLES F. VOLLMER.
